INTERNAL COMBUSTION ENGINE, MORE PARTICULARLY FOR SHIP PROPULSION

Oscar Simmen, Erlach, Switzerland, assignor to firm: Sulzer Frères Societe Anonyme, Winterthur, Switzerland

Application July 30, 1931, Serial No. 553,945, and in Switzerland August 23, 1930

1 Claim. (Cl. 123—140)

This invention relates to internal combustion engines, more particularly for the propulsion of ships, and has for its object to provide an improved construction of engine of the kind having a safety governor, that is to say a governor which, during normal operation of the engine, is inoperative but is adapted to come into operation if and when the engine speed becomes abnormal, as for instance in the case of ship propulsion if the propeller emerges from the water as may occur in a rough sea.

In an internal combustion engine according to the present invention there is combined with a control member for cutting off the fuel supply, a starting and stopping device and a safety governor both connected to and capable of acting on the control member. The invention is particularly applicable to multi-cylinder internal combustion engines and in this case the arrangement is conveniently such that the movement of the control member under the action of the safety governor cuts off the fuel supply to the various cylinders in succession, so that the cylinders are not put into and out of operation all together but consecutively. Further, with such an arrangement the movement of the control member under the action of the safety governor is preferably so limited that it can cut off the fuel supply to the majority only of the cylinders and permits the fuel supply to at least one cylinder to continue.

In order that movement of the control member by the starting and stopping device may be effected independently of the safety governor, lost motion is preferably provided between the safety governor and the control member. Thus, the control member may comprise a rod through which the starting and stopping device acts, and this rod may be connected to the safety governor through a coupling which only becomes operative to act on the rod after a predetermined movement of the governor so that, whereas the safety governor can cut off the fuel supply when the fuel pumps have been rendered operative by the starting device, yet the governor cannot cause the fuel pumps to be rendered operative when the fuel supply has been cut off by the starting device. That is to say, the safety governor is only operative when the starting device is in its "on" position.

The invention may be carried into practice in various ways, one construction according to this invention being diagrammatically illustrated by way of example in the accompanying drawing, in which

Figure 1 is a side elevation, partly in section,

showing one form of apparatus according to this invention, and

Figure 2 shows the position of the member putting the fuel pumps into and out of operation when the safety governor comes into action. 60

In Figure 1 is shown a form of the invention applicable to a four cylinder internal combustion engine. In this construction the four fuel pumps (not shown) for the individual cylinders are provided with inlet valves 1 arranged in casings 2 and controlled by springs 3. Arranged in chambers 7, through which fuel is delivered to the inlet valves 1, are relief cams 5 mounted upon rocking spindles 4 which are connected through levers 6 to a common coupling rod 8. The coupling rod 70 is connected by means of a rod 9 to one arm of a bell crank lever 15, the other arm of which is adapted to be acted upon by a push rod or plunger 13 having a crosshead 14. The crosshead 14 carries a roller which bears upon a cam 12 on a starting and stopping lever 11 which thus acts through the cam 12, push rod 13, lever 15 and rod 9 to move the coupling rod 8 and hence to rock the shafts 4 so that the relief cams 5 either raise the inlet valves 1 so as to render the fuel pumps inoperative, or permit these valves to seat themselves so that the fuel pumps come into operation. 75

The coupling rod 8 is connected also to one end of a rod 10 the other end of which is disposed within a cylinder 18 and is acted upon by one end of a spring 19, the other end of which acts on the end 21 of the cylinder. The cylinder is pivoted to one arm of a bell crank lever 17 the other arm of which is connected to the sleeve of a safety 90 governor 16. A stop 20 is provided on the rod 10 to limit the movement of the cylinder 18 along this rod. 85

The operation of the apparatus is as follows. When the starting and stopping lever 11 is in the position A it will be seen that all the suction valves 1 are lifted from their seats so that the fuel pumps are inoperative. When the engine is to be started, the lever 11 is moved from the position A to the position C whereby the cam 12 will be moved out of engagement with the roller on the crosshead 14, the bell crank lever 15 will be moved to the right by the action of the spring 19 acting on the rod 10, and the levers 6 will thus all be rocked to the right so that the valves 1 will be permitted to seat themselves under the action of their springs 3 whereby the fuel pumps are brought into operation. 100 105

During the operation of the fuel pumps the quantity of fuel injected may be regulated in a 110

manner well known per se by modifying the plunger strokes. This regulation is effected in accordance with the working conditions of the engine and will not be explained since it forms no part of the present invention.

If, however, the rotational speed of the engine becomes abnormally high, as for instance in the case of ship propulsion in the event of the propeller emerging from the water, the safety governor 16 will come into effective operation and will move the bell crank lever 17 from the position D to the position B. This bell crank lever will thus act through the cylinder 18 so that its end 21 comes into contact with the abutment 20 and thus moves the rod 10 and the coupling rod 8 to the left whereby the shafts 4 are rocked by the levers 6 so that the cams 5 lift the inlet valves 1 from their seats to render the fuel pumps inoperative. Below the excessive speed at which the safety governor 16 is designed to come into operation, this safety governor must have no effect on the coupling rod 8, and it will be seen that this is readily effected by reason of the clearance y which, during normal operation of the engine, is between the end 21 of the cylinder 18 and the abutment 20. It will further be seen that by moving the hand control 11 from the position C to the position A, the coupling rod 8 can be moved to the left independently of the governor 16, and this movement will take place against the action of the spring 19. Thus when the starting lever 11 is moved into the position C, it is the spring 19 which causes the movement of the rod 8 and of the levers 6, shafts 4 and cams 5, so that the springs 3 of the suction valves only have the suction valves themselves to operate and do not have to cause movement of the control mechanism. Moreover the spring 19 serves to prevent play in the parts of the control mechanism so that this mechanism operates in a noiseless manner.

In the modified construction shown in Figure 2 the arrangement is generally similar to that shown in Figure 1 except that the relief cams 5 are so angularly placed on their shafts 4 that when the fuel pumps are in operation the distances between the various relief cams and their associated valves are different. The result is that during the movement of the rod 8 to the right to bring the fuel pumps into operation by permitting their inlet valves to seat themselves, the valves of the various pumps are permitted to come into operation successively, while similarly, when the rod 8 is moved to the left to cut out the fuel pumps, the fuel pumps are cut out in succession and not all together, so that both during the starting and the stopping of the engine, the transition from one state to the other is smoother owing to which the engine, as well as the ship on which it is used, is protected from undesirable and injurious vibrations.

In this arrangement the movement of the safety governor is further so limited that it can only move the rod 8 a sufficient distance to completely cut off the fuel supply to three of the cylinders so that when the rod 8 is moved under the action of the safety governor, at least one cylinder will still be supplied with fuel. Thus the engine is never entirely cut out by the action of the safety governor whereby the action of this governor on the engine is made in such a manner as to avoid undesirable shocks and vibrations. In this connection it will readily be seen that if the safety

governor were to switch off simultaneously all the cylinders, for instance when the ship's propeller emerges from the water, and were simultaneously to switch all the cylinders on again when the propeller again became submerged, this action would be apt to produce undesirable vibrations in the whole ship. This disadvantage is avoided by the preferred arrangement shown in Figure 2 in which only the majority of the cylinders can be switched off by the safety governor and the switching-off of such cylinders is effected in succession and not all together.

In the construction shown in Figure 2 the position of the levers 6 during normal operation of the engine, that is to say when the starting lever 11 is in the position C, is marked *c*. When the safety governor 16 comes into operation the coupling rod 8 will be moved to the left only to such an extent that the levers 6 will assume the position *b*, this being ensured, for instance, by limiting the travel of the sleeve of the governor. In the position of the coupling rod 8 the extreme right-hand fuel pump will still continue to work, since there will still be a clearance x between the relief cam 5 and the suction valve 1 of this pump. On the other hand the suction valves 1 of the remaining pumps will be lifted from their seats respectively to the extent of clearances x , $2x$ and $3x$ so that these fuel pumps will be inoperative. When the hand control lever 11 is in the position A the coupling rod 8 will be in its extreme left-hand position, so that the levers 6 are in the position *a* wherein the suction valves of all the fuel pumps are raised so as to stop the engine.

It will be seen that with the constructions according to the present invention the same control apparatus for putting the fuel pumps into and out of operation can be used both for the manual control and for the control by the safety governor.

I claim:

In an internal combustion engine in combination, a plurality of cylinders, a fuel supply valve for each cylinder, a cam rotatably mounted upon a rocking spindle arranged in a fuel supply chamber provided in each cylinder, a lever fixed upon each of said rocking spindles, a rod connected to all of said levers, a starting-and-stopping device, a cam mounted on a shaft actuated by a handle of said starting and stopping device, a crosshead carrying a plunger slidably arranged in a guide and acted upon by said cam of said starting and stopping device, a bell crank lever having one arm cooperating with said plunger and one arm pivoted to one end of said rod, a cylinder slidably engaging the opposite end of said rod, a spring surrounding said end of said rod housed in said cylinder, a safety-governor, a bell crank lever having one arm pivoted to said cylinder and the other arm to a sleeve connected to said safety governor, and a shoulder on said rod adapted to be acted upon by said cylinder controlled by said safety governor, the arrangement of said levers being such, that all of them are fixed upon their rocking spindles under the same angle, whereby all of said control cams are operated to cut off the fuel supply if under the action of said safety governor said cylinder acts upon said shoulder on said rod.

OSCAR SIMMEN.
